US00D537409S

(12) **United States Design Patent** (10) **Patent No.:** **US D537,409 S**
(45) **Date of Patent:** **** Feb. 27, 2007**

(54) **COMBINED CHARGER AND INFRARED RAY EMITTER**

(75) Inventor: **Satoshi Suzuki**, Tokyo (JP)

(73) Assignee: **Sony Corporation**, Tokyo (JP)

(**) Term: **14 Years**

(21) Appl. No.: **29/251,490**

(22) Filed: **Jan. 10, 2006**

(51) **LOC (8) Cl. 13-02**

(52) **U.S. Cl. D13/108; D14/155**

(58) **Field of Classification Search** D13/107-110, D13/118-119, 184; D14/155, 251, 253, 432, D14/434; 320/107-115; 455/573

See application file for complete search history.

(57) **CLAIM**

The ornamental design for a combined charger and infrared ray emitter, as shown.

DESCRIPTION

FIG. 1 is a perspective view of a combined charger and infrared ray emitter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
